BOAT OAR MECHANISM

Lawrence A. Cummins, Toledo, Ohio

Application April 9, 1945, Serial No. 587,326

4 Claims. (Cl. 9—25)

1

This invention relates to power transmitting lever systems or mechanisms adaptable for rowing operations.

This invention has utility when incorporated as row boat front-facing oar readily attachable, adjustable, and even convertible to a rear-facing oar.

Referring to the drawings:

Fig. 1 is a fragmentary plan view of a row boat equipped with an embodiment of the invention, shown at say approximately a limit position for the rower or oarsman to commence the pull on the oar for urging the boat forward in the direction the rower is facing;

Fig. 2 is a side elevation of the mechanism of Fig. 1, at the oar stroke position in which the paddle of the oar is directly outward from the side of the boat or approximately perpendicular to the direction of boat transit;

Fig. 3 is a detail view, with parts broken away of the oar-lock or mounting for the device; and

Fig. 4 is an enlarged scale, partial side elevation of the mechanism of Fig. 2, in similar straight-out position, but as converted for the oarsman as pulling the oar handle toward his body, and facing toward the stern of the boat, thereby to urge the boat forward.

A row boat 1 is shown with a cross-seat 2 aft from its prow 3. Boat side or gunwale 4 near the seat 2 has rigidly mounted therewith a bracket device 5 with pivots 6 to provide a rockable mounting for a socket 7. Fixed with the socket 7 is an inwardly extending arm 8 spaced from the bracket 5 by a tension spring 9. This arm 8 is approximately 45° downwardly inclined from oppositely extending oval cross section tubular arm 10 when such arm is horizontal in its normal slide-guide functioning position.

An oar-lock stem 11 is in the socket 7 and as extending upwardly out of the socket 7 has spread arms 12 for horizontally extending axis or pivot pin 13 thru oar element 14, herein shown as a minor lever at its inner end having a hand grip portion 15. The lever 14 outer end has outwardly overhanging fork means at a pivot pin 16. The pivot pin 16 is embraced by an extension strap from a major length lever or element 17. The element 17 outer end is an oar blade or paddle 18 of straight or spoon type as may be desired.

The major lever 17 has a pivot pin or fulcrum 19. The lever 14 has a fixed fulcrum at the socket 7 in the pulling-of-the-oar for rowing direction of operation. To provide for ready knock-down handling, the pin 16 is removable.

2

The fulcrum 19 is a movable fulcrum projecting from and slideable with a guide block 20 directed by an oval cross section tubular floating third lever device in the mechanism. The third lever device 21 is an intermediate element in the oar mechanism. The lever 21 also has a movable fulcrum or pivot 22 in a guide block 23 movable along the tubular arm 10. These thin walled light metal tubular portions 10, 21, as terminally sealed against water leakage thereinto establish for the mechanism sufficiently low specific gravity to maintain buoyancy or float characteristics in the event of any overboard mishap.

The intermediate floating control lever 21 has a terminal pivot connection 24 which at one adjustment may engage at mid point 25 of the shorter arm or outward arm of the lever 14. Instead of this floating lever 21 connection with the lever 14 at the mid point 25, there is range for adjustment in the control transmission by locating the pivot pin 24 in a desired opening 26, 27, for either shorter or longer arm from the socket 7 of the lever 14 in its action upon the lever 21 to shift the fulcrum 19 of the lever 17 as modified by the guide arm 10 in controlling the fulcrum 22.

Due to the fact that the arm 10 carries the slide block 23 for the intermediate control lever 21 as the go-between for the lever sequences 14, 17, the oarsman, in the swinging of the paddle 18 clear of the water to bring such forward to start a working stroke for the oar, may depress the grip 15. This rocking is permitted by the pivotal mounting 6 for the socket and arm bracket means 7, 8, 10, and is yieldable due to the spring 9. The free or outward end of the arm 10 may swing up and down on the pivot 6. This freedom of movement allows the oarsman to direct the proper efficient dip of the oar blade 18 into the water on the working or pull stroke.

Operating advantages in the mechanism are present, not only for the oarsman to see directly the boat direction, but efforts expended in rowing have transmission efficiency. For instance with the pull unity on the handle 15 parallel to the boat side 4 adjacent the seat 2 at the forward or start position of Fig. 1, upon test demonstrates that the pull transmitted is twenty-eight percent of such unity inward 4" from the tip of a 35" blade to the fulcrum 19. The flat ellipse described by the fulcrum 19 in its orbit in the shift say from 30° away from the boatside to 45° upon pull test of unity demonstrates that here two tenths or twenty percent of such unity is transmitted perpendicular to the face of the blade 18 at 4" from its free end. For those two points

were the oar one-piece straight, the transmissions would be eighteen instead of twenty-eight percent, and fourteen instead of twenty percent.

Should the oarsman deem it desirable to convert the mechanism herein to a rear-facing oar, such is achieved by using a hole 28 in the lever 17, slightly away from the pivot 16, for a substitute pin 29 to engage the lever 21 as released from the arm 10, and thereby lock the element 21 with the lever 17 at this second point in addition to the block 20 at the fulcrum 19. Thus the connection of the element 21 at the pin 24 with the lever 14 assembles the three lever elements 14, 21, 17, as a rigid unit. The released arm 10 may swing against a catch 30 as the inner shorter arm 8 is clear for the element 14 to be used as a rigid oar element in the oar-lock 11, 12. An oarsman, sitting on the seat 2 and facing the prow 3, may grasp the oar portion 15. For a pull stroke of the mechanism, a drawing of the portion 15 is toward the seat 2 as the position of the oarsman changes from forward reach or incline to upright, or even leaning backward. The oar lever 14 is thus rocked on its fixed fulcrum 7. The movement of the grip 15 backward causes the other or outer end of the lever 14, thru the pivot connection 16, to thrust the arm 17 to swing on its fulcrum 19 for moving the paddle 18 in its outward rearward sweep. The extent of the dip of this rearward sweep of the paddle 18 in the water is determined by the applied downward tilt to the arm 10 thru lifting of the grip 15. The mechanism in this operation has an intermediate lever control for shifting the fulcrum 19 of the paddle carrying lever 17, 18. This is thru a compound or floating lever 21 having the pivotal connection 25 with the lever 14, the movable fulcrum block 23 on the arm 10, and the slide block connection 20 with the lever 17, 18. For the recover stroke, the oarsman depresses the grip 15 to lift the paddle 18 clear of the water, and then swings forward to the starting position in causing the grip 15 to move toward the prow 3 for a succeeding oar stroke.

What is claimed and it is desired to secure by Letters Patent is:

1. A power transmission mechanism comprising a support, a first lever, a fulcrum fixed on

the support for the lever, there being a rockable connection directly between the fulcrum and lever, a second lever terminally connected with the first lever, and a third control intermediate lever providing a fulcrum for the second lever movable relatively to the support and having connection with an arm of the first lever spaced from the first lever fulcrum.

2. A boat oar lock having a guide arm adapted to extend outwardly from the side of a boat upon which the oar lock is mounted, a sectional oar comprising a first hand-grip providing lever having a fixed fulcrum in the oar lock, a second paddle-providing lever terminally in series with the first lever, and a control intermediate lever having movable fulcrum mounting on the guide arm and spaced therefrom, a fulcrum for the second lever movable relatively to the first lever fulcrum.

3. A multiple lever oar assembly including two levers in series, one fixed and two movable fulcra, and, mounted by said fulcra, the said two levers in series and an intermediate lever, the latter lever extending between the two movable fulcra.

4. A front-facing boat oar mechanism including two levers having an in-series connection therebetween, mounting means providing two spaced apart fulcra, one for each of said two levers, and conversion means to back-facing oar assembly including holding means between the levers connecting one lever and its fulcrum, disconnectable mounting means for said holding means which when disconnected permits the holding means to move across the series connection between the two levers, and a lock cooperating between said holding means and the second lever to hold said two levers against articulation.
